ADJUSTABLE WINDOW SHADE ROLLER
BRACKET

Charles J. Kirchen, East St. Louis, Ill.

Application August 15, 1936, Serial No. 96,309

1 Claim. (Cl. 248—270)

This invention relates to window shade brackets or mountings and has for the primary object the provision of an efficient and inexpensive device of this character which when secured to a window casement may be adjusted vertically, longitudinally and horizontally with respect to said window casement to permit a shade carried thereby to be properly located with respect to the window and the securing of the bracket and mounting to the window casement without having to make specific measurements.

With these and other objects in view, this invention consists in certain novel features of construction, combination and arrangement of parts 15 to be hereinafter more fully described and claimed.

For a complete understanding of my invention, reference is to be had to the following description and accompanying drawing, in which

Figure 1 is a fragmentary front elevation illustrating a shade roller supported by a bracket or mounting constructed in accordance with my invention.

Figure 2 is a fragmentary top plan view illustrating the same.

Figure 3 is an end elevation illustrating the device.

Figure 4 is a fragmentary longitudinal sectional view showing the means for permitting the 30 horizontal and longitudinal adjustment of the device.

Figure 5 is a plan view illustrating a reversible shade roller attaching plate.

Figure 6 is a fragmentary vertical sectional view showing the means for permitting vertical adjustment of the shade roller.

Referring in detail to the drawing, the numeral 1 indicates a bracket or attaching plate including angularly related portions 2 and 3. The portion 2 has openings to receive screws or like fasteners 4 for mounting the bracket to a window casement or frame which positions the portion 3 horizontally. Said portion 3 is bifurcated, as shown at 5, to receive a bolt 6. The bolt 6 has a wing nut 7 threaded thereon. The

bolt 6 is employed for securing to the portion 3 plates 8 and 9 disposed on opposite sides of said portion 3. The plate 8 has end lips or flanges 10 engageable with opposite sides of the portion 3 of the attaching plate 1. The plate 9 is provided with spaced grooves forming seats for an arm 11. The arm 11 includes angularly related portions 12 and 13. The portion 12 is received in the grooves while the portion 13 is received between clamping plates 14 and 15. The clamping plates 14 and 15 are connected by a bolt 16 having a wing nut 17 threaded thereon. Integral with the head of the bolt 16 is a plate 18 having a slot 19 and an opening 20 permitting this device to be adapted to either end of a window shade roller 21. The arm 11 may be adjusted horizontally and longitudinally with respect to the portion 3 of the bracket or attaching plate 1 and the bolt 16 may be adjusted vertically with respect to the portion 13 of the arm 11. These 20 adjustments permit, after the mounting of the bracket and the connecting of the shade roller to the plate 18, the adjusting of the shade roller vertically, longitudinally and horizontally with respect to the window frame or casement. 25

The arm 11 is constructed of a single length of material bent upon itself to form the angularly related portions 12 and 13.

Having described the invention, I claim:

A window shade mounting comprising a bracket including an attaching portion and a supporting portion arranged at right angles to the attaching portion, an arm adjustably connected to the supporting portion and capable of being adjusted horizontally and longitudinally thereof, 30 said arm including angularly related portions, one of which being mounted on the supporting portion of the bracket and the other portion being disposed vertically, clamping plates adjustable on the vertical portion of the arm, a bolt connecting the clamping plates, and a plate formed on said bolt and having an opening and a slot whereby either end of the shade roller may be adapted thereto. 40
